V. SCHLEYER.
DEEP WELL PUMP LUBRICATION SYSTEM
APPLICATION FILED OCT. 30, 1920.

1,392,227.

Patented Sept. 27, 1921.

UNITED STATES PATENT OFFICE.

VICTOR SCHLEYER, OF ANDERSON, INDIANA, ASSIGNOR TO MIDWEST ENGINE COMPANY, OF INDIANAPOLIS, INDIANA, A CORPORATION OF INDIANA.

DEEP-WELL-PUMP-LUBRICATION SYSTEM.

1,392,227.

Specification of Letters Patent. Patented Sept. 27, 1921.

Application filed October 30, 1920. Serial No. 420,694.

To all whom it may concern:

Be it known that I, VICTOR SCHLEYER, a citizen of the United States, residing at Anderson, in the county of Madison and State 5 of Indiana, have invented a new and useful Deep-Well-Pump-Lubrication System, of which the following is a specification.

It is the object of my invention to provide an effective lubricating system for deep-well pumps, wherein the bearings of the 10 pump and its shaft may be well lubricated, and the lubricant kept from mixing with the water of the well save for the relatively small amount which may leak out through 15 the pump bearings.

The accompanying drawing illustrates my invention: The single figure of such drawing is a vertical central section through a deep-well pump embodying my invention, 20 with the intermediate part entirely broken away, and only a fragment of the upper part shown.

The pump casing 10 has a bottom inlet 11 and a top discharge 12, which latter 25 opens to a discharge pipe 13 which leads upward through the well to a discharge fitting 14. Within the pump casing 10 is a runner 15, of any convenient type, the pump being shown as having only a single runner though obviously it may have any desired number of runners. The pump runner (or runners) is mounted on a vertical shaft 16, which extends up axially through 30 the pipes 12 and 13 and is driven in any suitable manner by driving means at the top. Above the runner 15 the shaft 16 is provided with two bearings 17 and 18, the former being carried by the pump casing 10 and the bearing 18 being supported on an annular 35 flange 19 of the bearing 17. The bearing 18 has an annular foot 20 which is bolted to the flange 19, and which extends inward beyond such flange 19 to provide an inwardly projecting portion to which a separator plate 21 is bolted. A suitable gland 22 in the plate 21 surrounds the shaft 16 or a bushing thereon in the plate 21. Thus the plate 21 provides a space 23 below it and between it and the upper end of the bearing 40 45 50 55 60 65 70 75 80 85 90 95 100 105 110

a discharge chamber 26 in the footing 20. A series of lubricant-conducting pipes 27 surrounding the shaft 16 extends upward from the upper end of the bearing 18, thus providing an inner lubricant-conducting 60 passageway and an outer water-conducting passageway. Suitable bearings 28 may be located at intermediate points along the pipes 27, and supported in any convenient manner therefrom or from the water-discharge pipe 13, the manner of such support being immaterial to the present invention. At or near its upper end, the pipe 27 is provided with a supply pipe 29, which leads into the lower part of a lubricant tank 30, 70 preferably below a screen 31 provided in such tank to strain the lubricant which enters the pipe 29. The discharge chamber 26 is connected to the lower end of a lubricant-return pipe 32, the upper end of which 75 leads into the tank 30, preferably above the screen 31, and is preferably provided with a regulating valve 33 at some accessible point. In addition to the lubricant-return pipe 32, a pipe 34 is also connected to the discharge 80 chamber 26, preferably through a check valve 35 which permits flow from the discharge chamber to the pipe 34 but prevents it from the pipe 34 to the discharge chamber. The pipe 34 leads to the space 23, 85 which is in communication with the upper end of the bearing 17.

In operation, the shaft 16 is rotated in the usual manner, and the runners 15 and 25 thereon operate to move by centrifugal force the liquids in which they are immersed. The runner 15 moves water upward through the pipe 13 in the usual manner. The runner 25 circulates lubricant from the tank 30 through the pipes 29 and 27, to lubricate the bearings 28 and 18, drawing such liquid into the intake side of the runner and discharging it into the discharge chamber 26. From the discharge chamber 26, the liquid has two paths, one leading upward by the pipe 32 to the tank 30, to return to such tank most of the lubricant which was drawn therefrom, and the other by the pipe 34 to the space 23, to force lubricant positively through the main pump bearing 17. This latter lubricant escapes to some extent into the runner 15 and is carried upward with the ascending stream of water. Backflow of water through the bearing 17 and pipe 34 into the discharge 110

chamber 26 is prevented by the check valve 35. The outlet from the discharge chamber 26 through the pipe 34 to the space 23 is preferably smaller than that to the pipe 32, so that a relatively small amount of lubricant is forced through the bearing 17 and the greater part of the lubricant is returned by the pipe 32 to the tank 30. By manipulating the valve 33, it is possible to cut down 10 the flow through the pipe 32 and force more lubricant through the bearing 17, or vice versa, as conditions may require.

I claim as my invention:

1. In a deep-well pump, the combination 15 of a shaft extending down into the well, a rotary pump in the well and having a runner connected to said shaft, a water-discharge pipe extending up from said pump around said shaft, a main pump bearing 20 above the runner on said shaft, a lubricant-pump having a runner above said main pump bearing, a lubricant-conducting pipe surrounding said shaft and extending upward from the inlet of said lubricant pump, 25 and a connection from the discharge of said lubricant pump to said main bearing.

2. In a deep-well pump, the combination 30 of a shaft extending down into the well, a rotary pump in the well and having a runner connected to said shaft, a water-discharge pipe extending up from said pump, a main pump bearing above the runner on 35 said shaft, a lubricant-pump having a runner above said main pump bearing, a lubricant-conducting pipe surrounding said shaft and extending upward from the inlet of said lubricant pump, and a connection from the 40 discharge of said lubricant pump to said main bearing.

3. In a deep-well pump, the combination 45 of a shaft extending down into the well, a rotary pump in the well and having a runner connected to said shaft, a water-discharge pipe extending up from said pump, a main pump bearing above the runner on 50 said shaft, a lubricant-pump having a runner above said main pump bearing, a plate having a packing around said shaft and separating said bearing from said lubricant-pump, a lubricant-conducting pipe surrounding 55 said shaft and extending upward from the inlet of said lubricant pump, and a connection leading from the discharge of said lubricant pump to a point between said plate and said main bearing.

4. In a deep-well pump, the combination 60 of a shaft extending down into the well, a rotary pump in the well and having a runner connected to said shaft, a water-discharge pipe extending up from said pump, a main pump bearing above the runner on 65 said shaft, a lubricant-pump having a runner above said main pump bearing, a lubricant-conducting pipe surrounding said shaft and 70 extending upward from said lubricant pump, a lubricant tank to which the upper ends of both said lubricant-conducting pipes are connected, the lower ends of said two lubricant-conducting pipes being connected 75 respectively to the intake and the discharge of said lubricant pump to said main pump bearing.

5. In a deep-well pump, the combination 80 of a shaft extending down into the well, a rotary pump in the well and having a runner connected to said shaft, a water-discharge pipe extending up from said pump, a main pump bearing above the runner on 85 said shaft, a lubricant-pump having a runner above said main pump bearing, a plate having a packing around said shaft and separating said bearing from said lubricant pump, a lubricant-conducting pipe surrounding 90 said shaft and extending upward from said lubricant pump, a second lubricant-conducting pipe extending upward from said lubricant pump, a lubricant tank to which the upper ends of both said lubricant-conducting pipes are connected, the lower ends of said two lubricant-conducting pipes being connected 95 respectively to the intake and the discharge of said lubricant pump to a point between said plate and said main bearing.

6. In a deep-well pump, the combination 100 of a shaft extending down into the well, a rotary pump in the well and having a runner connected to said shaft, a water-discharge pipe extending up from said pump, a main pump bearing above the runner on 105 said shaft, a lubricant-pump having a runner above said main pump bearing, a lubricant-conducting pipe surrounding said shaft and extending upward from the inlet of said lubricant pump, a connection from the discharge of said lubricant pump to said main bearing, and a check valve in said last-named connection for preventing flow from 110 the main bearing to said discharge.

7. In a deep-well pump, the combination 115 of a shaft extending down into the well, a rotary pump in the well and having a runner connected to said shaft, a water-discharge pipe extending up from said pump, a main pump bearing above the runner on 120 said shaft, a lubricant-pump having a runner above said main pump bearing, a lubricant-conducting pipe surrounding said shaft and extending upward from said lubricant pump, a second lubricant-conducting pipe extending upward from said lubricant 125 pump, a lubricant tank to which the upper ends of both said lubricant-conducting pipes are connected, the lower ends of said two lubricant-conducting pipes being connected 130 respectively to the intake and the discharge.

of said lubricant pump, a connection from the discharge of said lubricant pump to said main pump bearing, and a check valve in said last-named connection.

- 5 8. In a deep-well pump, the combination of a shaft extending down into the well, a rotary pump in the well and having a runner connected to said shaft, a water-discharge pipe extending up from said pump, 10 a main pump bearing above the runner on said shaft, a lubricant-pump having a runner above said main pump bearing, a lubricant-conducting pipe surrounding said shaft and extending upward from said lubricant 15 pump, a second lubricant-conducting pipe extending upward from said lubricant pump, a lubricant tank to which the upper ends of both said lubricant-conducting pipes are connected, the lower ends of said two 20 lubricant-conducting pipes being connected respectively to the intake and the discharge of said lubricant pump, and a connection from the discharge of said lubricant pump to said main pump bearing, said last-named 25 connection being relatively restricted.

9. In a deep-well pump, the combination of a shaft extending down into the well, a

rotary pump in the well and having a runner connected to said shaft, a water-discharge pipe extending up from said pump, 30 a main pump bearing above the runner on said shaft, a lubricant-pump having a runner above said main pump bearing, a lubricant-conducting pipe surrounding said shaft and extending upward from said lubricant 35 pump, a second lubricant-conducting pipe extending upward from said lubricant pump, a lubricant tank to which the upper ends of both said lubricant-conducting pipes are connected, the lower ends of said two 40 lubricant-conducting pipes being connected respectively to the intake and the discharge of said lubricant pump, a connection from the discharge of said lubricant pump to said main pump bearing, and means for controlling the relative sizes of the two connections leading from the outlet of said lubricant 45 pump.

In witness whereof I have hereunto set my hand at Anderson, Indiana, this 26th 50 day of October, A. D. one thousand nine hundred and twenty.

VICTOR SCHLEYER.
